UNITED STATES PATENT OFFICE.

ANDREW J. COFFEE, OF PORTLAND, OREGON.

ELECTRIC-SIGNAL RECORDER.

SPECIFICATION forming part of Letters Patent No. 339,381, dated April 6, 1886.

Application filed November 24, 1885. Serial No. 183,865. (No model.)

To all whom it may concern:

Be it known that I, ANDREW J. COFFEE, of Portland, in the county of Multnomah and State of Oregon, have invented a new and Improved Electric-Signal Recorder, of which the following is a full, clear, and exact description.

This invention relates to certain new and useful improvements in the devices for giving fire-alarm signals; and the object of my invention is to provide a new and improved device for recording the signals by ink impressions on a paper strip.

The invention consists in the construction and combination of parts and details, as will be fully described and set forth hereinafter, and then pointed out in the claims.

Reference is to be had to the accompanying drawings, forming part of this specification, in which similar letters of reference indicate corresponding parts in both the figures.

Figure 1 is a longitudinal sectional elevation of my improved electric-signal recorder. Fig. 2 is a sectional plan view of the same.

The electro-magnet A is in the signal-line, and its armature B is secured to one end of the lever C, fulcrumed at D. A spring, D', draws the end of the lever C upward when it is released, and a check-screw, D'', limits the upward movement of the said lever. From one side of the lever C, at the end opposite the one carrying the armature, two pins or studs, E E', project, which are short distances from each other on an inclined line, and have curved or convex backs. A like pin or stud, F, projects from one side of the arm G' of a wheel, G, toward the lever C, the said wheel G being revolved by a clock-work mechanism, H, having the flier H'. The pins I and J project from the side of the wheel G, of which the pin J projects into the longitudinal slot K' on the lower end of the lever K, pivoted at K'', and having its upper end pivoted to the lever L, from one end of which the impression-block M, of rubber or other suitable material, projects downward. The opposite end of the lever L is provided with the transverse pin N, which passes into the slots N' in side pieces, N'', the said slots having their end parts extending upward from each other in the manner shown. The inking-pad O is placed below the impression-block M, and contains several

pieces of thick fabric, felt, &c., saturated with stamping-ink of any well-known kind. The strip P, of paper, is wound on the reel P', is 55 passed over the roller Q in front of the inking-pad O, over the platform Q', over the two rollers R and S, and is secured in the empty take-up reel T, which, with the reel P', is journaled in hangers projecting from the platform 60 Q'. The reel T is provided with a spring which revolves it to take up the slack of paper in the same manner that the slack of a window-shade is taken up by the spring shade-roller. The rollers R and S are mounted in 65 a frame, R', and springs R'', in the same, press the roller S against the roller R. The roller R is connected with the pinion U, which is revolved by the cog-wheel U', driven by the additional clock-work V, which runs synchronously 70 with the clock-work H. The clock-work V is locked by a rod, W', which can be acted on by a rod, W, extending to the clock-work H, and is provided with a downward bend, W'', on which the pin I can act. The 75 inking-pad O can be adjusted higher or lower, so that the inking-block M can easily rest on it.

The operation is as follows: When the circuit is broken to give a signal, the armature B is released from the magnet and is drawn 80 up by the spring D', whereby that end of the lever C provided with the studs E and E' is moved downward. The pin E is thus moved downward and disengaged from the stud F, whereby the wheel G is released and is revolved by the clock-work in the direction indicated by its arrow. The lower end of the lever K is moved by the pin J in the direction of the arrow a' and the upper end of the lever K, and with it the lever L, is moved in 85 the inverse direction of the arrow a'. The end levels of the slots N', acting on the pin N, depress one end of the lever L, and thereby the end carrying the block M is raised, and when said block is above the roller Q, the pin 90 N arrives at the other bevel of the slot, the marking-block M is moved down by the action of the bevels of the slots on the pin N, and an impression is made on that part of the paper strip on the roller Q. When the wheel G completes its revolution, the lever K is swung backward and the lever L and the printing-block M are brought back to their original position. When the pin I strikes the bend W'' of the 95 100

wire W, the said wire W is moved in the direction of the arrow b', and thereby the clock-work V is released and revolves the rollers R S, whereby the paper-strip P is unwound by said rollers from the reel P', the slack part of the strip being wound on the reel T. When the wheel G has made a complete revolution, its pin or stud F strikes the pin or stud E and is thus locked.

10 When the circuit is closed, the end of the lever C is swung up and the stud or pin F slides off the pin E and catches on the pin or stud E'.

The operation is repeated the next time the 15 circuit is broken, and thus an impression is made for each break in the circuit, and the signals given are automatically recorded on the strip P.

The clock-work V is stopped automatically 20 by the rod W', which is pushed down by a pin, m, on the cog-wheel U' coming in contact with said rod W when the said wheel U' has made a complete revolution. The lower end of the 25 rod W' comes in contact with a pin, o', on the small cog-wheel geared to the flier, and thus stops the clock-work.

The spring a on the rod W' actuates the same upward, when the said rod W' is pushed away from the pin m by the rod W, and the 30 spring b on the rod W holds the same in its normal position.

Having thus fully described my invention, I claim as new and desire to secure by Letters Patent—

35 1. The combination, with a clock-work, of an electro-magnet for releasing it, a printing-lever operated by the clock-work, an additional clock-work for feeding a strip of paper on which the impressions are made by the 40 printing-lever, and of a rod for releasing the printing-lever, and of a rod for releasing the paper-shifting clock-work from the clock-work operating the printing device, substantially as herein shown and described.

2. The combination, with a clock-work, of 45 a printing device operated by the same, an additional clock-work for feeding the paper on which the impressions are made, a reel containing the strip of paper, and a spring-reel on which the paper is wound, substantially as 50 herein shown and described.

3. The combination, with a clock-work, of the wheel G, operated by it, the pivoted lever K, acted on by the wheel G, the lever L, piv-

oted to the upper end of the lever K, the printing-block M on one end of the lever L, the pin N on the opposite end of the lever L, and the plates N', having the slots N', the ends of which are inclined upward from each other, substantially as herein shown and described.

4. The combination, with a clock-work, of 60 the wheel G, operated by it, the lever K, operated by the wheel G, the lever L, pivoted to the upper end of the lever K, and mounted to swing and move in the direction of its length, and of the printing-block M and ink-pad O, 65 substantially as herein shown and described.

5. The combination, with a clock-work, of 70 the wheel G, operated by the clock-work, the lever K, operated by the wheel G, the lever L, pivoted to the lever K, the printing-block M on the lever L, the inking-pad O, and the roller Q, over which the paper on which the impressions are to be made is passed, substantially as herein shown and described.

6. The combination, with a clock-work, of 75 the wheel G, provided with the pins or studs E E', the electro-magnet A, the lever C, carrying the armature B, the stud or pin F on the lever C, the lever K, operated by the wheel G, the lever L, pivoted to the upper end of the 80 lever K, and of a printing-block on the said lever L, substantially as herein shown and described.

7. The combination, with a clock-work mechanism, of the wheel G, provided with the pin 85 I, a printing mechanism operated by the wheel G, an electro-magnet for releasing the said clock-work mechanism, the additional clock-work mechanism V, for feeding a strip of paper, 90 and the rod W, for releasing the clock-work mechanism, on which rod W the pin I acts, substantially as herein shown and described.

8. The combination, with a clock-work mechanism, of the wheel G, operated by the same, 95 a printing mechanism operated by the wheel G, an electro-magnet for releasing the clock-work mechanism, the paper-reels P' and T, the rollers Q, R, and S, and an additional clock-work mechanism for revolving the roller R, 100 substantially as herein shown and described.
